UNITED STATES PATENT OFFICE.

JOSEPH BOURDAS SMITH BOOTH, OF ENFIELD, ENGLAND, ASSIGNOR TO LANSTON
MONOTYPE MACHINE COMPANY, OF PHILADELPHIA, PENNSYLVANIA, A COR-
PORATION OF VIRGINIA.

TYPOGRAPHIC COMPOSING-MACHINE.

1,079,326.

Specification of Letters Patent.

Patented Nov. 25, 1913.

Application filed June 3, 1912. Serial No. 701,241.

To all whom it may concern:

Be it known that I, JOSEPH BOURDAS SMITH BOOTH, a subject of the King of Great Britain, residing at "St. Kilda," First 5 avenue, Bush Hill Park, Enfield, in the county of Middlesex, England, have invented certain new and useful Improvements in Typographic Composing-Machines; and I hereby declare the following to be a full, 10 clear, and exact description of the same, reference being had to the accompanying drawings, forming a part of this specification, and to the figures and letters of reference marked thereon.

15 This invention relates to key-operated or manually controlled typographic composing machines, and refers particularly to machines for the production or composition of a record strip, controller or other governing 20 element of an automatic typographic or type casting and composing machine.

The chief object of this invention is to facilitate or simplify the composition of a pattern or governing element to produce in the 25 casting and composing machine tabular or like matter wherein a full or complete line comprises two or more separate justified sections which are associated together to form a complete line before the latter is transferred to a galley, the lines of a section being of uniform length so that the sections will assume properly their respective columns. These machines, for example as described in the specification of British Letters Patent No. 18,638 of 1899, (U. S. Patent No. 654,115, of July 17, 1900) whereon composition is effected by the manipulation of actuating keys (one for each character, 30 space and justification fraction) which are connected through permutation or like mechanism with punches or signal producing devices, are also provided with line-measuring and indicating mechanism for designating the justification signals required 35 for a particular line of composition. The measuring and indicating mechanism in the best known of the machines, comprises, as described in British specifications Nos. 15545/06 and 17199/08 (U. S. Patents No.

828,449, of Aug. 14, 1906, and No. 944,405, 59 of Dec. 28, 1909) a motor driven member conveniently in the form of a rack which is advanced, at each key operation, a certain distance corresponding to the unit value of the type or character signaled, and is provided with a shoulder or its equivalent so that near the end of the composition of a line this shoulder acts as a gage for another motor driven member or rack known as the justification rack for controlling the setting 60 of a justification scale or chart. In operation, keys, which produce signals denoting type both with respect to character and dimension, are actuated until all the matter that properly can be included in a line of 65 predetermined length has been set up, and the motor rack, which is advanced at each key operation, thereby brought into a position corresponding with the amount of matter composed in the line. If the line is not 70 exactly filled, the operator, by touching a special key, admits pressure to a cylinder connected with the justification rack which remains stationary until the composition of a line has been completed, and the rack is 75 advanced until stopped by the gaging shoulder on the motor rack, and through this motion the justification scale is set relatively to a justifiable space indicating pointer to indicate the justification keys which must 80 be operated to produce the required justification signals for the line.

With the arrangement above described, which in one form or another is common to machines of this class, the justification devices are only operative, in the true sense, near the end of the line, when composition has entered the justification area. It is true that by a hand operation of the justification mechanism, at any position in a full 90 line, as is often necessary when tabular work is being composed, the proper justification fraction can be ascertained, but such a method is complicated and lends itself to error. While these machines, therefore, 95 meet, in an exceedingly satisfactory manner, commercial requirements where what is known as straight matter is to be dealt with,

the operator, when composing tabular matter where two or more consecutive columns each existing as a separate entity in a full measure, and each requiring to be separately 5 justified, is forced, in order to justify these columns, to rely upon artificial methods and artifices which his knowledge of the capacities of the composing machine render possible. Such methods and manipulations all 10 increase the liabilities of error creeping in and reduce the otherwise possible speed of operation of the machine.

According to the present invention, the 15 justification devices are rendered responsive to the operation of the justification key or keys at any part of the line of composition so that where there are several separately 20 justifiable sections in a full measure, or where the production of the justification 25 signal or signals is or are required before composition has neared the end of the full measure or has entered the justification area as hitherto existing, each of these can be justified or the justification determined and accomplished as easily as in a line of full measure hitherto.

In accordance with this invention, there is provided, as heretofore, a measuring member movable in accordance with the unit 30 value of the characters or the like signaled, a second measuring member advanced to meet the first mentioned member and in addition thereto devices on the second member for automatically selecting one of a 35 series of justification abutments on the first measuring member. Conveniently the abutments consist of projections, stops or the equivalent thereof, one or another of which is adapted to act, in conjunction with a part 40 of the justification indicating mechanism, as a gage for the justification scale whenever the justification key is operated, whereby in place of a single justification area in a full measure, a series of justification areas 45 is provided and these stops are so spaced that one at least will be within a section or sub-measure. Conveniently these stops are carried by the motor rack of the existing machine, and the justification rack is provided 50 with a movable stop to co-act therewith. The stop on the justification rack is adapted, when the rack is moved, to engage one or other of the gages on the motor rack, and is held normally in a raised position 55 out of contact with the gages by a stationary abutment being removed from contact therewith and allowed to move or drop down into the path of the gages when the justification rack is moved.

60 The motor rack in the aforesaid machines drives an em-scale rack carrying a pointer to indicate on an em-scale the progress of composition and the rack is moved to or

returned to starting position before the composition of a new measure is commenced, 65 and in the composition of tabular matter the em-rack has to be moved by hand to the starting point for each column since, if the reversing or re-setting key is operated, the rack returns to its extreme initial position. 70 With the present invention, the columns in tabular matter, as set out on the em-scale, may overlap, and in order to facilitate the composition, a series of adjustable and separately acting zero stops for the em-scale, 75 is provided, these being adapted to move into operative position automatically and successively to constitute zero stops for the composition of the successive sections. Conveniently these stops act under gravity, 80 and normally rest upon the line measuring member, dropping down in succession behind it as the composition of the sections progresses. In addition to being capable of individual adjustment, these stops are also 85 so mounted as to be capable of being lifted simultaneously to permit the em-rack to return to the initial position for the commencement of composition of the full measure. The setting of these stops is facilitated 90 by a series of adjustable pointers acting in conjunction with the em-scale to indicate to the operator the end of the various sections in the complete line. The operator therefore having once set the devices, proceeds with the composition of tabular matter as hitherto in ordinary straight matter.

The invention will be described as applied to a composing machine as set forth in the specification of British Letters Patent No. 17,199/08 (U. S. Patent No. 944,405) but it is not limited in its application to this or to any other composing machine.

Referring to the drawings: Figure 1 is a partial front elevation and Fig. 1^a a similar view of the left hand extension of the line measuring and justification indicating mechanism of a composing machine embodying the present invention. Fig. 2 is a top plan view of Fig. 1^a. Fig. 2^a is a top 100 plan view of Fig. 1. Figs. 3 and 4 are sectional elevations of Fig. 1 showing the parts in relatively different positions, and Fig. 5 is a sectional elevation on the line 5-5 of Fig. 1^a.

105 The same reference letters indicate the same parts throughout the drawings.

It is not deemed necessary to give a detailed description of the already existing machine to which the invention is shown applied, it will suffice to refer briefly to the parts more intimately concerned with the present invention.

A is the motor rack which is advanced step by step during the composition of a 125 line of matter, and until a reversing or re-

setting key is operated, under constant driving pressure from the cylinder *a* and piston *a'*.

5 *B* is a pinion gearing with the rack *A* and connected to drive a units wheel *C*.

10 *D* is a units rack which, on the operation of any key, is brought into engagement with the units wheel and driven thereby, until a shoulder *d* on the units rack engages one of a series of unit stops *E* projected into the path of the shoulder *d* in accordance with the unit value of the character signal, and thereby the advance of the motor rack at each signal is determined.

15 *F* is a holding pawl which prevents the units wheel rotating when the units rack is withdrawn.

G is the em-scale.

20 *H* is the em-rack carrying a pointer *A* and driven forward from the motor rack by a pinion *c* on the shaft of the units wheel.

25 *J* is the justification rack and *J'* the driving motor therefor, to which pressure is admitted when the justification indicator key is operated.

30 *K* is the justification scale-drum or indicator which is geared to teeth *j* on the rack *J* by gearing *k*, and *I* is the zero stop for the line rack.

35 In the example illustrated, there is mounted on the motor rack *A* a series of stops *L* which act as gaging stops or abutments for the justification rack *J*. These stops may be situated at any desired distance apart but conveniently the distance between neighboring stops is equal to four ems, that being considered the narrowest columns wherein justifying types will be utilized in commercial working, and is sufficient to allow for a complete turn of the indicator drum *K* when advanced by its motor *J'* in response to pressure on the justification indicator key (not shown).

40 Co-acting with the stops *L* is a drop catch or stop *M* mounted upon the justification rack. This catch is loosely pivoted or hinged to the rack *J* and normally is held in the raised or inoperative position (see Fig.

45 3) by bearing against a stationary abutment *N* mounted above the motor rack when said justification rack is retracted. The catch *M* is thus held by the abutment *N* at a height to allow the motor rack to travel or advance during composition, but when

50 the justification key is operated and thereby pressure is exerted upon the piston *J'*, the rack *J* is advanced to the right and the catch *M* thereby being freed from the abutment *N* drops into engagement with the next approaching stop of the series *L* (see Fig. 4). At any position in the full measure therefore, there is always an available justifying area, the maximum capacity of

which is equal to four ems or one turn of the justification drum, and the justification mechanism is always responsive to the justifying key at whatever point in the line of composition it is operated. On the resetting key (not shown) being operated the justification rack returns to the position shown in Fig. 3 under the action of a spring *k'* and the motor rack and line scale rack also return until the latter is arrested by one or another of the stops *O* which latter act as the zero stop or initial points for the commencement of the various columns until after all the sections of a line have been composed and justified, when the stops are all raised and the re-setting key operated to return the parts to the initial position for the composition of a new line.

The stops *O* are mounted upon a frame or bar *O'* which is provided, on its underside, conveniently, with teeth or a rack *o* with which engages a worm wheel *o'* carried on each of the stops. Within each stop is a pivoted block *O²* which is pressed down upon the top of the frame or bar *O'* by a spring *O⁴* which acts to keep the worm wheel in engagement with the rack and prevents the accidental displacement of the stop. By applying a downward pressure to a stop at the top left hand corner it can be tilted on the pivot of block *O²* so as to disengage the worm from the rack when the stop can be moved freely along the bar. This provides for a rough setting of the stop, and a fine adjustment is provided by the worm and rack so that a stop can be accurately set relatively to the scale *o²*, which latter corresponds in its markings to the em scale *G*. Each stop is provided with a drop down portion *O⁵* which slides in a guideway in the body of the stop and normally rests upon the line rack, and when the end of the latter has passed said stop, the block *O⁵* drops down so as to form a zero stop for the rack when the reversing key for the motor rack *A* is operated. The drop-down parts of the stops are each connected by a link *O⁶* to a pin *O⁷* projecting through a slot *o³* in the body of the stop. A longitudinally movable bar *O⁸* is mounted within the frame *O'* and has two pins *O¹⁰* projecting into inclined slots *O⁹* in the frame so that when said rod is pushed longitudinally, the bar rises and when it engages the pins *O¹⁰* its further movement causes all the drop-down parts *O⁵* of the stops to be lifted, thus allowing the return of the line rack until arrested by zero stop *I*. The successive stops *O* form the zero points for the commencement of composition of the successive columns, and the approach to the justification area or to the end of a line of a particular column or section is notified to the operator by a series of pointers or

indicators P adjustably mounted upon the em scale.

The stops L instead of being in one with the motor rack as shown, may be adjustable 5 relatively to the rack so that the justification areas may be varied.

In setting the devices preliminarily to composing, the operator ascertains the ems in the full measure and then sets the normal 10 zero stop I for the line rack. He then counts the number of even ems, and, if required, the odd units in the first column, and sets one of the movable pointers P on the em scale at that distance from the pointer on 15 the line rack when the latter is against the stop I. The first movable stop O is then adjusted to a position such that when the re-setting key is operated the line rack will clear or will have cleared this stop which 20 acts as the zero stop for the second column. Assuming, as in the example illustrated in Fig. 1, that the full measure is one made up of three columns of 16 ems 8 units, 17 ems 10 units, and 19 ems 6 units, respectively, 25 the nearest convenient zero position to the 60 em mark on the line scale rack for the start of the first column is 40 ems, and at this point is now fixed the first movable pointer P. Counting back from this point 30 the 16 ems 8 units for the first column gives the zero or starting position on the scale as 56 ems 8 units, and the zero stop I is set to this point, or a movable stop O may be employed. The most convenient zero point for 35 the second column has next to be determined, and as the example chosen is a wide measure there is no necessity to crowd the stops together. A suitable finishing position for the second column is the 32 em point on the 40 scale at which the second pointer is placed. Counting back from this 32 em point, the necessary 17 ems 10 units gives the 29 ems 10 units position on the scale and at the corresponding points on its own scale the second 45 adjustable zero stop O is placed. The measure for the third column is 19 ems 6 units and the most convenient finishing point is found to be at the 16 ems point on the line rack at which the third pointer is fixed. 50 Counting 19 ems 6 units back from this gives the 35 ems 6 units position as the zero point for the column and at this the third zero stop is fixed. The determining consideration in selecting the positions is that the 55 zero or starting point at which an adjustable zero stop is to be placed is that it must fall between the zero points of two columns so that justifying and re-setting for the first column will not cause the stop for the third column but only that of the second, to fall, but that justifying and re-setting for the second column will cause the stop for the third column to drop.

Having now described my invention, what I claim as new is:

65

1. In a key-controlled typographic composing machine, the combination with a line-measuring device which is advanced in accordance with the unit-value, of each type signaled, and a second measuring device 70 that is advanced to meet the line-measuring device, of means on the second device for automatically selecting one of a series of justification abutments on the line-measuring device to determine the setting of a justification indicator, substantially as and for the purpose described.

2. A measuring and indicating mechanism for a key-operated typographic composing machine which is responsive to a key at any point in the composition of a line of matter in order to indicate the proper justification factor for the line, substantially as described.

3. In a key-controlled typographic composing machine furnished with a line-measuring member which is advanced in accordance with the unit-value of the type signaled and is provided with means for returning it at the end of a line against a zero-stop and a second measuring member advanced toward the line-measuring member to set a justification chart or indicator, the combination with the line-measuring member of a series of abutments with one or other of which a movable catch in the second measuring member is adapted to engage, and a series of separately acting stops automatically successively positioned to form zero stops for the line-measuring member, substantially as described.

85

4. In a key-controlled typographic composing machine the combination with a line measuring member and a second measuring member connected with a justification chart 105 or indicator and adapted to engage one or other of a series of abutments on the line-measuring member, of a series of separately acting stops automatically positioned to form successive zero stops for the line-measuring member, and mechanism for removing simultaneously all the zero stops from the return path of the line-measuring member with or without a series of adjustable pointers for a line-scale, substantially 110 as and for the purpose described.

100

5. In a key-controlled typographic composing machine furnished with a motor-driven line-measuring member or rack and controlled in its advance by a series of stops 120 and a justification member or rack advanced by a motor and operating a justification scale or indicator, of a series of abutments on the line-measuring member and a movable catch or stop on the justification 125 rack adapted to engage one or other of the

115

120

125

abutments on the line-measuring member but normally held out of engagement therewith by a stationary abutment, substantially as described.

- 5 6. In a key-controlled typographic composing machine furnished with a line-measuring member and a second measuring member advanced to meet the line-measuring member and connected with a justification scale or indicator, the combination with the line-measuring member of a series of ad-

justable stops each provided with a worm engaging a rack on which the stops are mounted, movable parts on the stops adapted to rest on the line-measuring member and to drop down behind and a movable rod for raising the stops, substantially as described. 15
